Primary Examiner — Cathron C Brooks*Assistant Examiner* — Ian F Whitmore*(74) Attorney, Agent, or Firm* — Keller Jolley Preece(57) **CLAIM**

An ornamental design for a display screen with graphical user interface, as shown and described.

DESCRIPTION

The FIGURE illustrates a front view of a display screen with graphical user interface.

The broken lines illustrate portions of a graphical user interface and form no part of the claimed design.

The outermost solid-line rectangle illustrates the perimeter of a display screen.
